United States Patent

Des. 234,940
Patented Apr. 22, 1975

234,940

BOTTLE

Mario Suso Mezquita, Zurbano 46, Madrid, Spain

Filed Jan. 9, 1973, Ser. No. 322,146

Term of patent 14 years

Int. Cl. D9—01

U.S. Cl. D9—83

FIG. 2

FIG. 1

FIG. 4

FIG. 5

FIG. 3

FIG. 1 is an elevational view of a bottle showing my new design, the opposite side being a mirror image of the side shown;

FIG. 2 is an elevational view looking from the right of FIG. 1;

FIG. 3 is an elevational view looking from the left of FIG. 1;

FIG. 4 is a top plan view; and

FIG. 5 is a bottom plan view thereof.

I claim:

The ornamental design for a bottle, as shown and described.
